(57) **CLAIM**

The ornamental design for a landscape edger, as shown and described.

DESCRIPTION

FIG. 1 is a perspective view of the landscape edger;
FIG. 2 is an enlarged perspective view of an end portion of the landscape edger shown in FIG. 1;
FIG. 3 is a top plan view thereof;
FIG. 4 is a front elevation view thereof;
FIG. 5 is a bottom plan view thereof;
FIG. 6 is a rear elevation view thereof;
FIG. 7 is a left elevation view thereof;
FIG. 8 is a right elevation view thereof;
FIG. 9 is a perspective view of an alternative embodiment of the landscape edger;
FIG. 10 is an enlarged perspective view thereof;
FIG. 11 is a top plan view thereof;
FIG. 12 is a front elevation view thereof;
FIG. 13 is a bottom plan view thereof;
FIG. 14 is a rear elevation view thereof;
FIG. 15 is a left elevation view thereof; and,
FIG. 16 is a right elevation view thereof.
